Application December 31, 1929, Serial No. 417,676
 Renewed April 16, 1934

16 Claims. (Cl. 49—5)

The present invention relates to improvements in glassware forming machines.

An important object of the invention is the provision of an improved type of machine of small size, embodying the feature of a single blank mold which forms and delivers blanks or parisons to a plurality of finishing molds. To this end the blank mold at regular time intervals places blanks at a transfer station and a pair of finishing molds 5 are brought one at a time to this station, receive blanks and then move to final blowing and discharge stations in succession.

Another object is the provision in a machine of the above character, of means for oscillating the finishing molds as a unit so that while one mold is positioned in the blank transfer station the other mold occupies the final blowing station, oscillation of the molds placing them alternately at said stations.

20 Other objects will be in part apparent and in part pointed out hereinafter.

In the drawings:

Fig. 1 is a part sectional side elevation of the improved glassware forming machine.

25 Fig. 2 is a front elevational view thereof.

Fig. 2A is a detail sectional view of a blow head.

Fig. 3 is a plan view.

Figs. 4, 5 and 6 are detail views showing the several successive positions occupied by the molds 30 during gathering and transferring of a blank. Fig. 4 shows the blank mold in charge gathering position. Fig. 5 shows the blank mold retracted and opened, leaving the blank suspended from the neck mold. Fig. 6 shows the finishing mold closed 35 about the blank, and both the neck and blank molds completely open.

Fig. 7 is a detail sectional view showing the vacuum control means.

Fig. 8 is a diagrammatic view showing the system of air motors for actuating the various mechanisms making up this machine, and the means for controlling operation of these air motors.

Fig. 9 is a detail sectional view showing the means allowing individual adjustment of the 45 cams.

In more or less general terms, the illustrated embodiment of my glassware forming machine comprises a single blank forming unit which may obtain mold charges of molten glass in any preferred manner and transform them into blanks or parisons, which, at a blank transfer position, are placed in finishing molds. This blank forming unit may, and preferably does, consist of partible co-operating neck and blank molds. At the 55 transfer position the blank mold opens, leaving a

bare parison suspended from the neck mold. Immediately, a finishing mold closes about the bare parison preparatory to final expansion of the latter. The neck mold then opens, leaving the parison entirely supported in and by the finishing 60 mold. At this point, this finishing mold is moved in a horizontal plane to a final blowing position where the blank or parison is expanded to its final shape. During such movement of said finishing mold, the blank forming unit obtains 65 another mold charge and carries it to the transfer position where, in the form of a parison or blank, it is enclosed in a second finishing mold, the latter being brought to the transfer position by movement of the first mold. The finishing 70 molds are then moved as a unit in a reverse direction and during such movement the finally shaped article in the first finishing mold is discharged so that the latter mold may receive another blank or parison when it again reaches the transfer position. In the present embodiment of the invention, the various operations and movements of the molds, etc. are obtained by air motors. Obviously, other means might well be employed in lieu of these motors.

More specifically, the illustrated embodiment of the machine comprises a blank mold unit 10 suitably supported on a frame 17 at the upper end of uprights 11 rising from a base 12. This blank mold unit 10 obtains mold charges at regular time intervals from a supply body 13 of molten glass in a tank 14 or furnace, which is provided with a gathering opening 15 through which a blank mold is alternately moved into and out of contact with the glass. The blank mold unit includes a pair of co-operating blank and neck molds 20 and 21, respectively, mounted on a ram 16, the latter carried by a slide 18 supported in inclined slideways 19 in a frame 17. The blank and neck molds are pivoted to a vertical hinge pin 22 depending from the outer end of the ram 16. Mechanism for opening and closing the blank and neck molds is so operated that the sections of the blank mold separate in advance of the opening of the neck mold. Such opening of the molds is necessary in order that the neck mold may remain closed a sufficient period of time to support the blanks or parisons during closing of the finishing molds, as will be apparent hereinafter. Alternate opening and closing of the blank and neck molds is obtained by mechanism including a pair of arms 23 (Figs. 1, 2 and 3) connected through links 24 to rock arms 25 pivoted on a hinge pin 26 carried by the ram 16. One of these rock arms is connected to a push rod 27 extend- 105

80

85

90

95

100

105

110

ing lengthwise through the frame 17, which rod carries a cam roll 28 constantly engaging a rocker arm 29. This arm 29 is rocked at regular time intervals by an air motor 30 (Figs. 1 and 8) which 5 includes a differential piston 30^a to one side of which air under pressure is constantly supplied through a pipe 31 from the main supply pipe 32. Air under pressure is supplied intermittently to the opposite side of the piston 30^a through a pipe 10 33 leading from the valve box 34, the latter connected through a pipe 35 to said main pipe 32. A valve 36 (Fig. 8) regulates and controls the supply of air under pressure to the motor 30 and is opened at regular time intervals by a rotary cam 15 37 mounted on a continuously rotating cam drum 38 to which motion is imparted by a motor 39 or the like operating through gearing 40.

A plunger 41 (Fig. 6) adapted to co-operate with the neck mold in forming blanks, is suitably 20 secured to a plunger holder 42 mounted at one end of a lever 43, which in turn is pivoted to a horizontal hinge pin 44 carried by the ram 16. The inner end of this lever 43 carries a cam roll 45 which periodically engages a stationary cam 46 25 adapted to rock the lever in a manner to retract the plunger 41 from the cavity of the neck mold 21 just prior to arrival of the blank mold unit at the blank transfer position. The plunger is moved by gravity into the neck mold at other times.

30 Mold charges are gathered into the blank mold by exhausting the air from the mold cavity during contact between the mold and supply body of molten glass. This exhaust of air is accomplished by providing a passageway 16^a (Figs. 4 and 7) 35 extending lengthwise through the ram 16, one end of said passageway communicating with the neck and blank mold cavities (Fig. 4), while the other end is formed with a port 16^b leading to an annular channel 16^c which constitutes part of vacuum 40 control means. The inner end of the ram is formed integral with the slide 18, the latter having an opening 18^a into which a vacuum supply pipe 18^b slidably fits, said pipe 18^b having a port 18^c or ports adapted for register with the annular 45 channel 16^c. Such registration is effected only while the blank mold 20 is in contact with the glass or in close proximity thereto. Vacuum may be applied to the pipe 18^b in any preferred manner.

50 Charge severing means by which excess glass is severed from the gathered mold charges, comprises a vertically swinging knife 47 (Figs. 1, 4, 5 and 6) pivoted to the arm 16. This knife is connected to operating mechanism through an arm 55 48, the latter pivoted to a rod 49 which in turn is suitably connected to a bell crank lever 50. This lever 50 is pivoted to the slide 18 which carries the ram 16 and has a cam roll 51 thereon adapted to ride in a cam 52, the latter suitably 60 secured to a portion of the frame 17 and so shaped that when the ram 16 is fully projected, the lever is positioned at one end of the cam to hold the knife as shown in Fig. 4. As the ram is retracted, the cam roll 51 rides up and then down through 65 the inverted V shaped portion of the cam 52 so that the bell crank lever is oscillated and imparts a corresponding movement of the knife 47. In this manner, the knife is swung across the lower 70 end of the blank mold at a predetermined point following initial retraction of the mold from the gathering position and is then swung back to the inactive position (Fig. 5) prior to beginning of the blank transfer operation.

75 Reciprocation of the blank and neck molds 20

and 21, respectively, along an inclined path between the charging and blank transfer positions is obtained by an air motor 53 (Figs. 1, 2, 3 and 8) mounted on the upper side of the frame 17 and operatively connected to the ram 16. The differential piston 54 is connected to a slide 55 and through this slide to a rack and gear mechanism 56, including a rack bar secured to the upper side of the slide 18. Air under pressure is constantly supplied to the air motor 53 through a pipe 57 leading from the main supply pipe 32. A pipe 58 (Figs. 1 and 8) provides communication between the air motor and the valve box 34 referred to heretofore. A valve 59 adapted to be actuated by the rotary cam 60 at regular time intervals, regulates and controls the supply of air under pressure to the motor 53, in a manner to cause intermittent operation of the air motor and therefore alternate projection and retraction of the ram 16 at regular time intervals.

The finishing mold mechanism includes a finishing mold carriage 62 or table arranged beneath the blank mold unit 10, said carriage mounted on a stationary pillar 63, about which it oscillates at regular time intervals. A 100 portable finishing mold 61 is arranged at each end of the carriage 62 (Figs. 1, 2 and 3), there being provided carriers 64 individual to the finishing molds providing for relative vertical movement between the molds and carriage 62. Each 105 finishing mold carrier 64, of which there are two in the present disclosure, is secured to the upper end of a slide 65 forming a part of the mold carrier and mounted for vertical reciprocation in a pair of slideways 66. Vertical reciprocation of the carrier 64 is obtained by means including a roller 67 suitably connected to the lower end of the slide 65 and adapted to be engaged by a crosshead 68 carried by an air motor 69, the latter arranged at the blank transfer position. This 110 air motor is connected to the main supply line 32 through a pipe 69^a and to a valve box 81 through a pipe 69^b. A valve 69^c actuated at regular time intervals by a rotary cam 69^d controls 115 intermittent flow of air under pressure to the motor so that the latter operates in timed relation to movements of the remaining mechanisms. Downward movement of the finishing mold carriers 64 is limited by adjustable stops 85 suitably 120 secured to the slideways 66.

The finishing mold sections are connected through mold arms 70 to a vertical hinge pin 71 on the carrier 64 and thence through suitable 125 links 72 to a slide 73 which is operated at regular time intervals to alternately open and close said mold. This slide 73 is mounted in slideways 74 extending lengthwise of the carrier 64 and is provided with a cam roll 75, which, when the finishing mold is in final blowing position, is positioned in a holder 76, the latter carried at the 130 outer end of a piston rod 77 forming part of an air motor 78. One motor 78 is provided for each finishing mold. Air under pressure is constantly supplied to one end of the motor 78 through pipes 79 which are directly connected to the 135 main pipe line 32. Air under pressure is intermittently supplied to the other ends of the motors 78 through pipes 80 leading to the valve box 81 which is suitably connected to the main pipe line 32 through a pipe 82. Valves 83, actuated by rotary cams 84, control and regulate supply of air under pressure to the motors 78. These 140 cams 84 are mounted on a drum 38 which is continuously rotated by the motor 39.

145 Directly opposite the blank transfer position is 150

arranged means for closing the finishing molds 61 about blanks or parisons suspended from the neck mold 21. This means comprises an air motor 110 disposed between and in the plane of the motors 78 which open the molds, said motor 110 mounted on the central pillar and carrying a holder 111 which at regular time intervals engages the rolls 75 on the finishing mold slides 73. When a bare blank is in position to be enclosed in a finishing mold 61, the motor 110 is operated and causes movement of the holder 111 and slide 73 in a direction to close the mold. Actuation of this motor 110, which includes a differential piston (not shown), is obtained by constantly supplying air under pressure to one side of the piston through a pipe 112. This normally places the holder 111 in its innermost position where one of the cam rolls 75 may move into operative relation thereto. A supply pipe 113 connects the motor 110 and the valve box 81, the latter having a valve 114 opened periodically by means of a rotary cam 115. Thus, air under pressure is supplied to the motor 110, at regular time intervals, to cause movement of the holder 111 for the purpose of closing the finishing molds.

The bottom plate 86 (Figs. 1, 3, 5 and 6) is pivoted to a horizontal hinge pin 87 carried by the slide 65. A roller 88 on the lower side of the bottom plate rides on a track 89 (Figs. 2 and 3) including a vertically movable section 90 which is rigidly connected by means of an arm 91 to the crosshead 68, so that when the crosshead 68 is moved vertically to raise or lower the finishing mold unit, corresponding movement is imparted to the bottom plate 86. This feature will be described in detail hereinafter.

A blow head 92 (Figs. 2, 2A and 3) is arranged at each of the final blowing stations "B" and is adapted to be brought into operative engagement with the upper end of a finishing mold at regular time intervals as part of the operation through which blanks or parisons are expanded in the finishing mold. Each blow head 92 is in the form of an inverted cup secured to the outer end of an arm 93 pivoted for vertical swinging movement upon the upper end of a post 94, the latter rising vertically from the base 12. The arm 93 is rocked periodically for the purpose of operatively and inoperatively positioning the blow head 92 in alternation, such rocking motion being obtained by an air motor 95 mounted on the post 94 and connected through a rod 96 to a finger 97 on the blow head arm 93. Air under pressure is constantly supplied to one end of each air motor 95 through a pipe 98 leading to the main pipe line 32 (Fig. 8) for the purpose of holding the blow head 92 out of contact with the finishing mold. At regular time intervals, air under pressure is supplied to the other end of the air motor 95 through a pipe 99. One of the pipes 99 leads to the valve box 34 (Fig. 8), while the other pipe leads to the valve box 81, flow of air through both of said pipes being controlled by valves 100 which are alternately opened and closed by rotary cams 101 carried by the drum 38.

Each blow head 92 is connected to any suitable source of supply of air under pressure through a flexible pipe 102 which may extend downwardly through the post 94, as shown. Air under pressure is automatically applied to the blanks or parisons in the finishing molds upon seating of a blow head on the corresponding finishing mold. This is obtained by means of a disc 103 arranged within a blow head and carried by a valve rod 104. This valve rod 104 extends upwardly through the

blow head and carries a coil spring 105 which normally holds the disc 103 in its lowermost position. While in this position, a passageway 106 through the valve rod is out of communication with the supply pipe 102. The passageway 106 is brought into communication with the supply pipe 102 due to seating of the blow head upon the finishing mold whereby said disc 103 is brought into contact with the blank in the finishing mold and moved upwardly against spring 105.

Oscillation of the finishing mold carriage 62 for the purpose of moving the finishing molds 61 to and from the various positions, is obtained by an air motor 120 (Figs. 1, 3 and 8). The piston rod 121 is suitably connected to an arm 122 on the sleeve 123 supporting the carriage 62, said sleeve rotatively supported on the pillar 63. Air under pressure is constantly supplied to one end of the motor 120 through a pipe 124, thereby normally holding the carriage in one of its extreme positions. A pipe 125 connects the other end of the motor 120 to the valve box 34 wherein a valve 126 is provided to control flow of air to said motor. A rotary cam 127 on the drum 38 periodically opens the valve 126 and thereby permits flow of air under pressure to the motor. Thus, the motor is operated at regular time intervals, causing oscillation of the finishing mold carriage.

For the purpose of varying the timed relation between the operating periods of the various mechanisms, each rotary cam is adjustably mounted on its drum. The drum (Fig. 9) is formed with grooves individual to the cams. Screws 128 are employed to secure the cams in any adjusted position on the drum. By changing the relative positions of the cams on the drums, it is obvious that the time intervals between operations of the motors will be changed and cause a corresponding change in the operation of the other mechanism.

During operation of this machine, the cam drum 38 (Figs. 2 and 8) is rotated continuously and thereby causes operation of the several air motors in a predetermined order. The air motor 53 operates to project the ram 16 so that the lower end of a blank mold dips into the supply body 13 of molten glass, such projection of the ram causing register of the ports 16^b, 18^c (Fig. 7) in the vacuum supply line so that the air is exhausted from the blank and neck molds 20 and 21, respectively. Such operation fills the mold cavities with molten glass. Retraction of the ram beyond a predetermined point shuts off the application of vacuum to these molds and places the latter in a blank transfer position. The shear 47 removes excess glass from the mold charge as the ram begins its retractive stroke. During gathering of the mold charge, the finishing mold table 62 is moved in a horizontal plane so that one of the finishing molds 61 is placed in the blank transfer position directly opposite the opening 15 in the tank. Simultaneously with, or prior to, reaching the blank transfer position, the blank mold 20 is opened, leaving a bare parison suspended from the neck mold. The finishing mold, after it has completed its horizontal movement to the transfer station, is raised a predetermined distance so that when it closes about the bare parison, its upper end will contact with the lower side of the neck mold 21. The air motor 110 is now operated to close the finishing mold about the parison, such closing movement being followed immediately by opening of the neck mold 21. The ram 16 will now be again projected for the purpose of gathering another mold.

140
145
150

charge, and during such operation, the finishing mold carriage 62 is moved so that the finishing mold 61, to which a blank has just been transferred, is carried to a position directly beneath one of the blow heads 92. Incidentally, such positioning of the finishing mold carries the cam roll 75 to a position within one of the holders 76 so that said mold is positively held closed during final expansion of the blank or parison. The air motor 95 is operated to move the blow head 92 into contact with the upper end of the finishing mold. As described above, the disc 103 (Fig. 2A), upon seating of the blow head on the finishing mold, moves upwardly and causes communication between the passageway 106 and the pipe 102 so that air under pressure may be supplied to the finishing mold. Thus, the blanks are expanded to final shape. During such final expansion of the blank or parison, a blank is being transferred to the other finishing mold in the manner above described. Upon completion of final shaping of the blank, one of the motors 78 is operated to open a finishing mold, it being understood that prior to such opening, the blow head 92 has been swung upwardly away from the mold. This open finishing mold is now moved in a reverse direction toward the blank transfer position, while the other finishing mold moves away from the transfer position to the final blowing position "B" beneath the other blowing head 92. The bottom plate 86 supports the expanded article just freed from the finishing mold until the latter reaches the discharge position "C" between the blowing position "B" and said blank transfer position. At this discharge position, the track 89 is shaped to allow the bottom plate 68 to tilt so that an article supported thereon is deposited in a chute 136 for delivery to a conveyor 137.

40 Modifications may be resorted to within the spirit and scope of the appended claims.

What I claim is:

1. In combination, a blank mold mounted for reciprocation along an inclined path between charging and blank transfer positions, means for moving the mold, means for delivering a mold charge of molten glass to the mold and transforming it into a blank prior to reaching the transfer position, a finishing mold carriage 50 mounted for oscillation in a horizontal plane below the transfer position, a finishing mold on said carriage, means for moving the carriage to thereby successively place the finishing mold in blank transfer, final blowing and article discharging positions, means for transferring a blank to the finishing mold at the transfer position, means for finally expanding the blank, and means for discharging the expanded blank from the finishing mold.

60 2. In combination, a blank mold mounted for reciprocation along an inclined path between charging and blank transfer positions, means for moving the mold, means for delivering a mold charge of molten glass to the mold and transforming it into a blank prior to reaching the transfer position, a finishing mold carriage mounted for oscillation in a horizontal plane below the transfer position, a pair of horizontally spaced finishing molds on said carriage, means 65 for oscillating the carriage to thereby cause one finishing mold to occupy the blank transfer position while the other finishing mold is in a blowing position, means for transferring blanks to the finishing molds at the transfer position, means 70 for blowing the blanks to final shape, and

means for discharging finished articles from the finishing molds at a discharge station between blank transfer and blowing positions.

3. In combination, a blank mold mounted for reciprocation along an inclined path between charging and blank transfer positions, means for moving the mold, means for delivering a mold charge of molten glass to the mold and transforming it into a blank prior to reaching the transfer position, a finishing mold carriage mounted for oscillation in a horizontal plane below the transfer position, a pair of horizontally spaced finishing molds on said carriage, means for oscillating the carriage to thereby cause one finishing mold to occupy the blank transfer position while the other finishing mold is in a blowing position, means for transferring blanks to the finishing molds at the transfer position, means for blowing the blanks to final shape, means for discharging finished articles from the finishing molds at a discharge station between blank transfer and blowing positions, and means for alternately raising and lowering the finishing mold at the transfer position to move said mold into and out of position to enclose a blank.

4. In a glassware forming machine, a blank forming unit comprising a partible blank mold and a co-operating partible neck mold above and in register with the blank mold, said molds mounted for reciprocation along an inclined path between charging and blank transfer positions, means for moving said unit, means for delivering mold charges of molten glass to the molds and transforming them into blanks prior to reaching the transfer position, a finishing mold carriage 105 mounted for movement in a horizontal plane below the transfer position, a pair of partible finishing molds mounted on said carriage, means for moving said carriage to alternately place the finishing molds in blank transfer and final blowing 110 positions, means for opening the blank mold at the transfer position and leaving a blank suspended from the neck mold, means for alternately raising and lowering the finishing molds at the transfer position to move them into and out of contact with the neck mold, means for closing the finishing molds around the suspended blanks, means for opening the neck mold, means for blowing the blanks to their final shape in the blowing positions, and means for discharging the 115 blown blanks from the finishing molds at discharge stations between the transfer and blowing positions.

5. In a glassware forming machine, a blank forming unit comprising partible co-operating blank and neck molds mounted for reciprocation along an inclined path between charging and blank transfer positions, means for moving said unit, means for delivering mold charges of molten glass to the molds and transforming them into blanks prior to reaching the transfer position, a finishing mold carriage mounted for movement in a horizontal plane below the transfer position, a pair of partible finishing molds mounted on said carriage, means for moving said carriage to alternately place the finishing molds in blank transfer and final blowing positions, means for opening the blank mold at the transfer position, means for alternately raising and lowering the finishing molds at the transfer position to move them into and out of contact with the neck mold, means for opening the neck mold, means for closing the finishing molds, means for blowing the blanks to their final shape in the blowing positions, and means for discharging the blown blanks 120

- from the finishing molds at discharge stations between the transfer and blowing positions, said means for raising and lowering the finishing molds comprising a vertically movable track, an air motor for alternately raising and lowering the track, and means operating in timed relation to movements of the blank forming unit and the finishing molds for actuating the air motor. 5
6. In combination, a blank forming unit comprising a blank mold, means for delivering mold charges of molten glass to the mold and transforming them into blanks, a finishing mold carriage arranged below the blank forming unit and movable in a horizontal plane, a pair of partible finishing molds spaced apart horizontally on said carriage, means for oscillating the carriage to alternately place the finishing molds in blank transfer and final blowing positions, means for transferring blanks to the finishing molds at the transfer position, means for supplying blowing air to the finishing molds at the blowing positions, and means for opening the finishing molds at discharge stations individual to the finishing molds between the transfer and final blowing 20 positions. 25
7. In a glassware forming machine, the combination of a finishing mold carriage mounted for oscillation in a horizontal plane, a partible finishing mold thereon, means for oscillating the mold carriage to alternately place the finishing mold in blank transfer and final blowing positions, means for forming blanks and transferring them to the finishing mold at the transfer position, means for expanding the blanks in said mold 30 at the final blowing position, and means for discharging finished articles from the mold between said positions. 35
8. In a glassware forming machine, the combination of a finishing mold carriage mounted for oscillation in a horizontal plane, a finishing mold carrier mounted for vertical movement on said carriage, a partible finishing mold on said carrier, means for oscillating the mold carriage to thereby alternately place the finishing mold in blank transfer and final blowing positions, means including a partible neck mold for forming and transferring blanks to the finishing mold, means for alternately raising and lowering the finishing mold carrier at the transfer position to cause operative engagement between the finishing mold and neck mold, means for finally expanding the blanks at the blowing position, and means for discharging the expanded blanks at a discharge station between said positions. 45
- 55 9. In a glassware forming machine, a finishing mold carriage mounted for oscillation in a horizontal plane, a pair of vertically movable finishing mold carriers mounted on said carriage, means for oscillating said carriage to thereby move the finishing molds one at a time to a blank transfer position, said movement placing one mold in a final blowing position while the other occupies the blank transfer position, means including a partible neck mold for forming blanks and transferring them to the finishing molds at the transfer position, means for alternately raising and lowering the carriers at the transfer position to cause operative engagement between the finishing molds and neck mold, means for closing the finishing molds at the transfer position, means for expanding the blanks to the form of finished articles at the blowing positions, and means for discharging the articles during movement of the finishing molds to the transfer position. 70
10. In a glassware forming machine, a finishing mold carriage mounted for oscillation in a horizontal plane, a pair of vertically movable finishing mold carriers mounted on said carriage, means for oscillating said carriage to thereby move the finishing molds one at a time to a blank transfer position, said movement placing one mold in a final blowing position while the other occupies the blank transfer position, means including a partible neck mold for forming blanks and transferring them to the finishing molds at the transfer position, means common to both finishing molds for alternately raising and lowering the carriers at the transfer position to thereby cause operative engagement between the finishing molds and neck mold, means for closing the finishing molds about the blanks, means for then opening the neck mold, means for expanding the blanks to the shape of finished articles at the blowing positions, and means for discharging the finished articles. 80
11. In a glassware forming machine, the combination of a finishing mold carriage mounted for oscillation in a horizontal plane, a pair of finishing molds thereon, means including an air motor for oscillating the carriage to thereby place the finishing molds one at a time in blank transfer and blowing positions in alternation, means for forming and transferring blanks to the finishing molds at said transfer position, means for expanding the blanks at the blowing positions, means for opening the finishing molds at said blowing positions, and means for discharging finished articles from the molds during movement of the latter to the blank transfer position. 100
12. The combination of a mold carriage, finishing molds thereon, means for oscillating the carriage about a vertical axis and thereby moving the molds to a transfer station, a non-rotating carrier, a parison mold thereon, means for reciprocating the carrier in a direction transverse to that in which the finishing molds approach the transfer station, and thereby reciprocating the parison mold between a charge receiving position and the transfer station, and means for transferring parisons from the parison mold to the finishing molds. 105
13. In a machine for forming glass articles, the combination of a mold carriage, means for causing the mold carriage to travel intermittently, a carrier thereon, a mold supported on said carrier, a mold bottom mounted on said carrier for up and down movement to and from the mold, a stationary cam controlling the up and down movements of the mold bottom during the travel of the mold carriage, said cam comprising a section movable up and down, means for moving said carrier upward on the mold carriage and thereby lifting the mold while the mold carriage is at rest, and means for causing said cam section to move upward with said carrier and thereby cause the mold bottom to move up with the mold while the carriage is at rest. 115
14. In a machine for forming glass articles, the combination of an intermittently traveling mold carriage, a mold thereon, a mold bottom on said carriage movable toward and from the mold, a stationary cam controlling said movements of the mold bottom, said cam including a movable section, means for moving the mold up and down on the carriage while the latter is at rest, and means for moving said cam section up and down with the mold. 120

prising a partible blank mold and a partible neck mold above and in register with the blank mold, a carrier on which said molds are mounted, means for reciprocating the carrier along an 5 inclined path between a mold charging position and a blank transfer position, means for delivering mold charges of molten glass to the molds at said charging position, means cooperating with the molds for transforming the charges 10 of glass into blanks prior to reaching the transfer position, a finishing mold carriage, a pair of partible finishing molds mounted on said carriage, means for oscillating said carriage horizontally and thereby moving each finishing mold 15 alternately to the blank transfer and final blowing positions, means for opening the blank mold at the transfer position and thereby leaving a parison suspended from the neck mold, means for raising and lowering each finishing mold at 20 the transfer position to move it into and out of engagement with the neck mold, means for closing each finishing mold about a parison sus-

pended from the neck mold while the finishing mold is in said lifted position, means for opening the neck mold, and means for blowing the parisons to their final shape in the finishing molds.

16. In a glassware forming machine, the combination of a finishing mold carriage mounted for oscillation in a horizontal plane, a partible finishing mold thereon, means for oscillating the mold carriage to alternately place the finishing mold in blank transfer and final blowing positions, a ram, a blank mold carried thereby, means for reciprocating the ram in an inclined direction and thereby moving the blank mold from a charge receiving position to said transfer position, means for forming blanks in the blank mold and transferring them to the finishing mold at the transfer position, means for expanding the blanks in said finishing mold at the final blowing position, and means for then opening the mold.
